US0D1048620S

(12) **United States Design Patent** (10) Patent No.: **US D1,048,620 S**
Chen et al. (45) Date of Patent: ** Oct. 22, 2024

(54) **ELECTRODE**

(71) Applicant: **Contemporary Amperex Technology Co., Limited**, Ningde (CN)

(72) Inventors: **Congsheng Chen**, Fujian (CN); **Zetao Ye**, Fujian (CN); **Wenfa Lin**, Fujian (CN); **Yu Ding**, Fujian (CN)

(**) Term: **15 Years**

(21) Appl. No.: **35/519,699**

(22) Filed: **Nov. 14, 2023**

(80) **Hague Agreement Data**

Int. Filing Date: **Nov. 14, 2023**

Int. Reg. No.: **DM/234374**

Int. Reg. Date: **Nov. 14, 2023**

Int. Reg. Pub. Date: **Jan. 19, 2024**

(30) **Foreign Application Priority Data**

Aug. 23, 2023 (CN) 202330542878.8

(51) **LOC (14) Cl.** **13-02**

(52) **U.S. Cl.**

USPC **D13/121**

(58) **Field of Classification Search**

USPC D13/119, 120, 121

CPC H01M 12/02

See application file for complete search history.

(57) **CLAIM**

The ornamental design for an electrode as shown and described.

DESCRIPTION

1. Electrode
2. Electrode
- 1.1 : Front
- 1.2 : Back
- 1.3 : Left
- 1.4 : Right
- 1.5 : Top
- 1.6 : Bottom
- 1.7 : Perspective
- 1.8 : Perspective
- 2.1 : Front
- 2.2 : Back
- 2.3 : Left
- 2.4 : Right
- 2.5 : Top
- 2.6 : Bottom
- 2.7 : Perspective
- 2.8 : Perspective
